DEVICE FOR ATTACHING ELECTRIC FIXTURES

Filed Feb. 21, 1924

Patented Mar. 3, 1925.

1,528,583

UNITED STATES PATENT OFFICE.

SVEN MARTIN STREED, OF MINNEAPOLIS, MINNESOTA.

DEVICE FOR ATTACHING ELECTRIC FIXTURES.

Application filed February 21, 1924. Serial No. 694,233.

To all whom it may concern:

Be it known that I, SVEN MARTIN STREED, a citizen of the United States, residing at Minneapolis, in the county of Hennepin and State of Minnesota, have invented certain new and useful Improvements in Devices for Attaching Electric Fixtures; and I do hereby declare the following to be a full, clear, and exact description of the invention, such as will enable others skilled in the art to which it appertains to make and use the same.

My invention relates to electric light fixture attaching devices, and to this end it consists of the novel devices and combinations of devices hereinafter described and defined in the claims.

Electric light fixtures are usually attached to outlet boxes, covers, face plates and similar elements secured directly or indirectly to metal conduits for electric wires not only as a matter of convenience but to afford a ground for the fixtures, which is usually required by ordinance.

As is well known, such boxes and conduits are placed in buildings and the wiring roughed in before the lathing and plastering is done, and the boxes are usually out of true in respect to vertical or horizontal planes and hence when the fixtures are attached thereto, such fixtures are either held out of plumb or do not project at the proper angle from a wall or ceiling.

Furthermore, the finished walls or ceilings are very often not true, which adds to the difficulty of properly hanging or attaching electric light fixtures.

My invention has for its object to overcome the above difficulties in hanging or attaching the electric light fixtures, and in its preferred form may be readily attached to standard electric equipment without altering the same, and includes a turnable fixture-attaching stud that is free to oscillate to properly hold a fixture, and when a fixture is suspended therefrom, will automatically move into a position to hold the same plumb. The fixture-attaching stud may also be adjusted into a position to be held from turning when attaching a fixture thereto or removing the same therefrom. Said stud may also be adjusted into a position to be held against oscillatory movement.

In the accompanying drawings, which illustrate the invention, like characters in-

dicate like parts throughout the several views.

Referring to the drawings:

Fig. 1 is a view principally in central vertical section showing the invention suspending an electric light fixture from an outlet box;

Fig. 2 is a view principally in bottom plan with some parts sectioned on the line 2-2 of Fig. 1;

Fig. 3 is a perspective view of the fixture-attaching stud;

Fig. 4 is a bottom plan view of the cap removed from the outlet box;

Fig. 5 is a detail view principally in section showing the stud lifted into the cap for interlocking engagement therewith to be held from turning; and

Fig. 6 is a detail view showing the stud applied to an outlet box positioned for application in a wall, and which stud is turned into a position for engagement with the cap to prevent oscillatory movement.

The numeral 7 indicates the joists of a floor in a building, and to which joists is secured a ceiling 8 of lath and plaster. Set into the ceiling 8 is an inverted outlet box 9 having an axially located hole 10, four radially offset holes 11 closed by knockout discs 12 and a plurality of wide screw holes 13 arranged in diametrically opposite pairs. One end of a conduit 14, located between the joists 7, extends through one of the holes 11 from which the respective disc 12 has been removed. The outlet box 9 is readily secured in the conduit 14 by an opposing nut 15 and a bushing 16, both of which have screw-threaded engagement with said conduit. The numeral 17 indicates the suspending pipe of an electric light fixture, not shown, the numeral 18 indicates a canopy slidably mounted on said pipe and held in different longitudinal adjustments thereon by a set screw 19 and with its upper end in contact with the ceiling 8.

A hickey 20 has screw-threaded engagement with the upper end of the pipe 17 and through which hickey electric light wires 21 in the conduit 14 extend into the pipe 17. The parts thus far described are all of standard and well known construction and have been illustrated simply for the purpose of showing the invention embodied therein.

The invention, as illustrated, includes a stud 22, a cap 23, the former of which has

a head 24 and is provided with screw threads, both external and internal, as indicated at 25 and 26, respectively. A transverse lock slot 27 is formed in the head 24 and the top of said head is reversely beveled toward said slot, as indicated at 28, for a purpose that will presently appear. The under side of the head 24 is beveled or of conical formation, as indicated at 29. 10 The fixture stud 22 is inserted through the hole 10 from the back of the box 9 and its conical surface 29 rests on said box and supports the stud 22 with freedom for universal oscillatory movement in all directions. 15 The hickey 20 is screwed onto the fixture stud 22 and thereby supports the pipe 17 and parts carried thereby from said stud.

The cap 23, as shown, is of elongated 20 formation and is supported on the back of the outlet box 9 and has a recess 30 to receive the head 24. On the bottom of the recess 30 is an elongated lock lug 31. As one means for attaching the cap 23 to the 25 outlet box 9, I provide said cap at one end with a hook-like hinge lug 32 and at its other end with a nut-equipped screw stud 33. This lug 32 and the stud 33 are so spaced that they may be inserted into two of the 30 diametrically opposite screw holes 13 and be interlocked with the cap to detachably secure the same to the box 9, as best shown in Fig. 5.

The upper edges of the beveled surfaces 35 28 are in substantially the same plane as the face of the lock lug 31 so that the fixture stud 22 is normally free to rotate within the recess 30 without engaging said lug. To hold the fixture stud 22 from turning 40 when screwing the hickey 20 thereon or removing the same therefrom, it is only necessary to move said stud endwise onto the recess 30 to cause the lock slot 27 to receive the lock lug 31, as shown in Fig. 5. After 45 a ceiling fixture is attached to the stud 22, said stud will drop out of interlocking engagement with the lug 31 when said ceiling fixture is released.

In attaching side lights to wall outlet 50 boxes, as shown in Fig. 6, the fixture stud 22 may be turned so that its beveled surfaces engage the lock lug 31 and the lock slot 27 extends transversely thereof, to hold the stud 22 against oscillatory movement.

55 As the stud 22 is normally in contact with the box 9, the ground for the electric light fixture is complete.

What I claim is:

1. A headed fixture-attaching stud, a cap 60 adapted to be attached to a commercial outlet box having an aperture in its back, said stud being adapted to be inserted into said box through said aperture before the cap is applied thereto and with its head engaging said box as a bearing on which it is free

to turn, and lock elements arranged to be interlocked by an axial movement of the stud into the cap from said bearing and temporarily hold said stud from turning.

2. The structure defined in claim 1 in 70 which said stud and cap have opposing cam-acting surfaces arranged to be engaged by a turning movement of the stud in the cap to cam said stud onto its bearing and frictionally hold the same from turning. 75

3. A fixture attaching stud having a beveled head in which is a lock slot, and a cap having an internal lock lug arranged to enter said lock slot, by an axial movement of the stud into the cap, to hold the stud 80 from turning in the cap, said stud being adapted to be inserted into a commercial outlet box through an aperture in the back thereof with its head engaging said box as a bearing, said cap having attaching means 85 arranged to be interlocked with said outlet box through certain holes therein, said beveled head being arranged when the outlet box affords a bearing therefor to frictionally engage the lock lug by a turning 90 movement of the stud to hold said stud from further turning movement.

4. The combination with a wall or ceiling outlet box having in its back an aperture, of a fixture-attaching stud having a tapered head and insertable in said box through the aperture therein with its head engaging said back as a bearing with freedom for turning movement thereon, a cap for the head of the stud attached to the back of the box, 100 and lock elements on said head and cap arranged to be interlocked by an axial movement of the stud into the cap.

5. The combination with a wall or ceiling outlet box having in its back an aperture, 105 of a fixture-attaching stud having a tapered head and insertable in said box through the aperture therein with its head engaging said back as a bearing with freedom for turning movement thereon, a cap for the head of the stud attached to the back of the box, and lock elements on said head and cap arranged to be interlocked by an axial movement of the stud into the cap, said cap having a hook-like hinge lug and a nut-equipped screw stud secured to the head of the outlet box by inserting the same through certain holes therein. 110

6. The combination with a wall or ceiling outlet box having in its back an aperture, 115 of a fixture-attaching stud having a tapered head and insertable into said box through the aperture therein with its head engaging said back as a bearing with freedom for turning movement thereon, a cap for the head of the stud attached to the back of the box, and lock elements on said head and cap arranged to be interlocked by an axial movement of the stud into the cap, said cap 120 having a hook-like hinge lug and a nut- 125 equipped screw stud secured to the head of the outlet box by inserting the same through certain holes therein.

equipped screw stud secured to the head of the outlet box by inserting the same through certain holes therein, said head having a beveled surface arranged to frictionally engage the lock lug by a turning movement of the stud to hold the stud from further turning movement.

7. The combination with a wall or ceiling plate, of an endwise movable fixture-attaching stud turnably mounted on said plate for oscillatory movement, and a cap on the plate having a lock lug, the head of said stud having a transverse lock slot arranged to

receive the lock lug when said stud is moved endwise into the cap to hold said stud from turning.

8. The structure defined in claim 7, in which said head is reversely beveled away from the lock slot for engagement with the lock lug when said stud is turned into a position in which the lock slot extends transversely of the lock lug to hold said stud against oscillatory movement.

In testimony whereof I affix my signature.

S. MARTIN STREED.
